ARRANGEMENT FOR THE PRINTING OF
FORMS COVERED WITH ELASTIC FOIL

Artur Büttner, Heidelberg, Germany, assignor to
Schnellpressenfabrik Aktiengesellschaft Hei-
delberg, Heidelberg, Germany, a corporation of
Germany

Application January 2, 1952, Serial No. 264,407

Claims priority, application Germany
March 2, 1951

9 Claims. (Cl. 101—391)

1

In the relief printing of printing forms, the manufacture of which in the usual construction is very expensive, it is known to cover a printing form, made of any suitable material, by a thin elastic skin and to draw this skin, which may consist of for instance, a rubber foil, firmly onto the form by providing a negative pressure, so that all contours and surfaces of the form stand out clearly. The impression on the paper is then effected by the inked rubber skin. The sections which, after the application of the rubber skin, constitute the printing form proper, are laid on a smooth bed plate, which is fitted directly onto the type bed of a high-speed cylinder press, or into a platen press, so that the form, upon withdrawal of the air, only has to be sealed off in an upward direction. However, it is not possible with these bed plates to print, in a single operation, forms which also contain, in addition to the sections to be printed, type consisting of metal or wooden characters, or of block sections, which are of normal height.

An object of the present invention is to provide an arrangement by means of which it is possible, simultaneously to set up normal metal or wood type, or type-high printing blocks, with sections of any suitable material placed on a bed plate of suitable height, and to carry out the printing thereof in one operation. According to the invention, the arrangement for relief printing by means of an elastic skin which covers the printing form and which is maintained on the latter by negative pressure, consists of a chase for the form, which is closed in air-tight fashion against the type bed, and carries the foil in air-tight fashion. The chase is preferably provided on its upper face with a surrounding groove which communicates with the space enclosed by said chase and which is covered by an elastic skin, said chase being provided on its underside with a yieldable packing strip. This packing strip can be clamped in a recess formed in the underside of the chase, the space enclosed by the recess and the chase being adapted to be connected to a source of pressure medium in order that the packing may either be pressed onto the support by providing a negative pressure, or withdrawn into the chase recess by means of suction air, the latter operation being for the purpose of more readily removing the chase. Due to the arrangement of the packing strip, all inequalities in the support are equalized, so that by the application of the packing strip by means of compressed air, a cushion of compressed air is placed around the chase before the air located between the elastic skin and the chase is drawn off.

2

The groove formed in the upper face of the chase thus retains the elastic skin in position under the action of the negative pressure or vacuum upon the withdrawal of air from the internal space of the chase, said skin being held taut over the form in such manner that the contours of the form stand out in relief fashion. By means of this arrangement, it is possible for the first time to print in one operation a mixed type bed of characters of normal height, type-high printing blocks and letters, or picture sections, placed on a support of suitable height, this operation also being possible on platen presses.

For a better understanding of the invention and to show how it may be carried into effect, the same will now be more fully described with reference to the constructional example illustrated in the accompanying drawing, wherein:

Figure 1 is a plan view of a corner of a printing chase;

Figure 2 is a cross section thereof;
Figure 3 is a cross section showing a modified arrangement, and

Figure 4 is a section on the line IV—IV of Figure 1.

The chase consists of a central bar 1 which is enclosed at both sides by supporting bars 2, 3 which project beyond the central bar 1 in a downward direction, the bars 1, 2 and 3 being held together by screws 4. The supporting bars 2, 3 are formed on their inner sides with grooves 5 which are located approximately at the level of the lower edge of the central bar 1 and which are associated with corner grooves 6 formed in the central bar 1. Engaged in these grooves 5, 6 are the edge beads 7 of a packing strip 8. A bore 9 leads from the lower face of the central bar 1 to a threaded hole 10 into which is screwed a nipple 11 arranged to provide a connection to the pressure pipe of a pump.

The center bar 1 is formed in its upper face with a groove 12, and ducts or bores 13 extend from the groove 12, through the supporting bar 3, to the inner face of the latter.

A type bed 14 of a printing machine such as, for example, a high-speed cylinder press, accommodates the chase 1—3 with the form enclosed therein. The type bed is formed with bores 15, 16 which communicate with a collecting duct 17, and the latter according to Figure 2 is provided with a nipple 18 to which there is connected a hose 19 leading to the suction pipe of a vacuum pump.

Instead of the suction bores 15, 16 and the duct 17 being arranged in the type bed, it is also possible, as indicated in Figure 3, for the chase to

accommodate a tube connection 20 to provide for the connection of the suction pump.

For printing purposes, the printing form is clamped in the chase 1-3 by a locking arrangement a-b-c and strip d. This form, for example, may consist of normal metal or wood type letters e and support 21 for embossed printing characters 22, all of which are placed with the chase on the type bed 14, and then covered by a foil 23 which also covers the groove 12. By applying a slight positive pressure through 10-11 to the space 24 located between the center bar 1 and the packing strip 8, the packing strip is forced against the type bed 14 and thereby seals off the chase against the type bed to make it air tight. The space enclosed by the type bed 14 the chase 1-3 and the foil 23, thus sealed, is then subjected to negative pressure or vacuum by connection 18, or connection 20, so that the foil 23, held by the edges of the grooves 12, conforms accurately to the contour of the form. In this way, the positive pressure in the space 24 can be increased.

Upon completion of the printing operation, the negative pressure in the space enclosed by the chase 1-3 is again nullified, and also the space 24 is relieved of the positive pressure, so that a negative pressure can be produced in this space 24 in order to lift the packing strip 8 completely from the type bed 14, or other support. The foil 23, for instance, a rubber cloth, can then be removed, and the chase 1-3 can also be lifted in known manner from the type bed 14.

For the purpose of withdrawing air from the space enclosed by the chase 1-3, it is possible to employ the same suction pump as is provided on these printing presses for the sheet delivery means.

I claim:

1. In a printing press for use with an elastic foil, a type bed, a chase on the type bed, a printing character support surrounded by said chase in spaced relation to the inner side of the chase, said chase comprising a central frame bar having an upwardly opening groove on its upper face and a bore for connecting said groove with the space between the inner side of the chase and the printing character support, supporting side bars projecting below said frame bar to provide a space between the chase and the type bed, a flexible packing member in said space, a pressure connection on the chase communicating with the inner side of the packing member to expand the same into contact with the type bed, and means for connecting a source of vacuum with the inner portion of the chase to draw a foil into said groove thereof and also draw the foil over the printing characters on the support within the chase.

2. In a printing press for use with an elastic foil, a type bed, a chase on the type bed, a printing character support surrounded by said chase in spaced relation to the inner side of the chase, said chase comprising a central frame bar having an upwardly opening groove on its upper face and a bore for connecting said groove with the space between the inner side of the chase and the printing character support, supporting side bars projecting below said frame bar to provide a space between the chase and the type bed, a flexible packing member in said space, a pressure connection on the chase communicating with the inner side of the packing member to expand the same into contact with the type bed, and means in the type bed comprising a nipple

and passageways communicating with the area within the chase and about the type character support to cause a foil to be drawn by vacuum pressure over the printing characters on the support within the chase.

3. In a printing press for the printing of a form releasably covered with an elastic foil, a type bed mounted in said press, a printing form mounted on said type bed, printing characters mounted on said form, a chase mounted on said type bed and around said printing form having the printing characters mounted thereon, means for locking said printing form in said chase, said means being positioned between the form and the chase, an elastic foil covering both said printing form having the printing characters thereon and said chase, positive pressure means for sealing the chase against the type bed, said means being operatively connected to said chase, and negative pressure means for the air-tight sealing of said elastic foil against said chase and said printing form, said means being operatively connected to said type bed and said chase.

4. In a printing press for the printing of a form releasably covered with an elastic foil, a type bed mounted in said press, a printing form mounted on said type bed, printing characters mounted on said form, a chase mounted on said type bed and laterally spaced around said printing form, said chase having on its upper side a surrounding groove, said chase and said printing form having a space therebetween, means for locking said printing form in said chase, said means being positioned in said space between said printing form and said chase, an elastic foil covering both said printing form having the printing characters thereon and said chase including said surrounding groove, positive pressure means for sealing the chase against the type bed, said means being operatively connected to said chase and including a packing strip on the underside of said chase and adjacent said type bed, and negative pressure means for the air-tight sealing of said elastic foil against said chase and said printing form, said means including means for operatively connecting said surrounding groove on the upper side of said chase with the said space between the chase and printing form, said negative pressure means being operatively connected to said type bed and said chase.

5. In a printing press for the printing of a form releasably covered with an elastic foil, a type bed mounted in said press, a printing form mounted on said type bed, printing characters mounted on said form, a chase mounted on said type bed and around said printing form, said chase having a recess on its underside opposite said type bed, a packing strip clamped in said recess forming a space between it and said chase, means for locking said printing form in said chase, said means being positioned between the form and the chase, an elastic foil covering both said printing form having the printing characters thereon and said chase, positive pressure means for sealing the chase against the type bed, said means being operatively connected to said chase at the space between it and said packing strip, and negative pressure means for the air-tight sealing of said elastic foil against said chase and said printing form, said means being operatively connected to said type bed and said chase.

6. In a printing press for the printing of a form releasably covered with an elastic foil, a type bed mounted in said press, a printing form mounted on said type bed, printing characters mounted on

said form, a chase mounted on said type bed and around said printing form having the printing characters mounted thereon, said chase including a frame bar and supporting bars at each side of said frame bar, said supporting bars projecting below the frame bar thus forming a recess, a packing strip clamped between the said supporting bars at a distance from said chase and adjacent said type bed, means for locking said printing form in said chase, said means being positioned between the form and the chase, an elastic foil covering both said printing form having the printing characters thereon and said chase, positive pressure means for sealing the chase against the type bed, said means being operatively connected to said chase, and negative pressure means for the air-tight sealing of said elastic foil against said chase and said printing form, said means being operatively connected to said type bed and said chase.

7. In a printing press for the printing of a form releasably covered with an elastic foil, a type bed mounted in said press, a printing form mounted on said type bed, printing characters mounted on said form, a chase mounted on said type bed and around said printing form, said chase and said printing form having a space therebetween, means for locking said printing form in said chase, said means being positioned in said space between said printing form and said chase, an elastic foil covering both said printing form having the printing characters thereon and said chase, positive pressure means for sealing the chase against the type bed, said means being operatively connected to said chase, and negative pressure means for the air-tight sealing of said elastic foil against said chase and said printing form, said means including a suction means connected to the said

space between the chase and the printing form, said space being operatively connected to said chase at the surface covered by said elastic foil and to the type bed at its surface adjacent to the chase.

5 8. In a printing press for the printing of a form releasably covered with an elastic foil, a type bed mounted in said press, a printing form mounted on said type bed, printing characters mounted on said form, a chase mounted on said type bed and around said printing form, means for locking said printing form in said chase, said means being positioned between the form and the chase, an elastic foil covering both said printing form having the printing characters thereon and said chase, positive pressure means for sealing the chase against the type bed, said means being operatively connected to said chase, and negative pressure means for the air-tight sealing of said elastic foil against said chase and said printing form, said means being operatively connected to said type bed and said chase and including a suction pipe passing through said chase.

10 20 25 9. The apparatus of claim 8 including a sheet feeding and delivery means for said printing press and a suction pump connected to said suction pipe, for said sheet feeding and delivery means.
